UNITED STATES PATENT OFFICE.

ALEXANDER RATTRAY AYSON, OF MOSGIEL, NEW ZEALAND.

DETACHABLE HANDLE FOR PAILS.

SPECIFICATION forming part of Letters Patent No. 728,072, dated May 12, 1903.

Application filed September 22, 1902. Serial No. 124,477. (No model.)

To all whom it may concern:

Be it known that I, ALEXANDER RATTRAY AYSON, a subject of the King of Great Britain and Ireland, residing at Mosgiel, in the Colony of New Zealand, have invented certain new and useful Improvements in Detachable Handles for Pails; and I do hereby declare the following to be a full, clear, and exact description of the invention, such as will enable others skilled in the art to which it appertains to make and use the same.

This invention relates to improvements in detachable handles for pails and the like applicable in making a bucket from an empty kerosene-tin or other vessel without it being necessary to perforate the sides of the vessel, the main feature of the invention constituting a removable fastening applicable for various purposes.

It is an advantage when a vessel is worn out to be able to transfer the handle readily to a new one. Again, on placing a vessel with contents over a fire it is frequently best to remove the handle, and when the vessel is to be removed again attach it, and these operations are easy with my invention.

Besides having a semicircular or other well-known form of handle or stem with perforated lower end or ends, my device consists of four parts, (some of which may be permanently united, if desired,) and when all the parts are assembled with the vessel in proper position the fastening is complete.

Referring to the accompanying drawings, which illustrate the invention, Figures 1 and 2 are front and back elevations, and Fig. 3 a transverse section through the line 5 in Fig.

1. Fig. 4 is a side elevation showing a modification.

40 x shows part of the upper edge of a vessel to which the invention is applied.

a shows a handle or stem apertured at b and provided with means, as hereinafter described, for detachably securing the same to the vessel without perforating the latter or without requiring lugs or other attachments on the vessel. Said detaching means for the handles comprise the pins e , preferably screw-threaded, as shown, provided with the ad-

jacent gripping-plates c and d , which are 50 adapted to be carried by said pin-support e on one side of each end of the handles, so that when the pins e , which pass through the apertures b , are moved transversely of the handles by any suitable means, such as the wing-nut f , the clamping-plates c and d , located adjacent each other on the same side of each handle end, are moved together and clamp the sides of the vessels for detachably securing the handle thereto. 60

Instead of pivotally connecting the ends a of the handle directly on the pin or support e I prefer to adopt the construction clearly illustrated in Fig. 3, wherein c' represents a hollow bearing or sleeve provided with the 65 centrally-apertured annular flange comprising the gripping-plate c . This sleeve or bearing c' is loosely mounted in the aperture b of the handle a and forms a journal for the screw-threaded pin e . The sleeve or bearing c' is of a length sufficient to pass completely through said aperture b , so that the boss c^2 of the wing-nut f , being of greater diameter than the aperture b , engages the end of the sleeve c' when tightened up and allows 70 the handle to oscillate freely on the sleeve or bearing, or instead of this arrangement I sometimes find it convenient and advantageous to adopt the modified construction shown in Fig. 4, wherein the apertures b 75 through the ends of the handles are sufficiently large to receive the boss c^2 of the wing-nut f , which in this construction engages directly with the annular gripping-plate c , the hollow sleeve-bearing c' being dispensed with 80 and the boss c^2 acting in its stead.

d' represents an inwardly-projecting indenting lip or flange at the lower end of the clamping-plate d , the said indenting-flange being preferably so disposed relatively to the gripping-plate c as to engage the sides of the vessel directly beneath the lower edge of the plate c . Thus when the plates are clamped together the sides of the vessel are indented for more securely fastening the gripping-95 plates thereto, as shown at x' in Fig. 3.

It is obvious that the gripping-plate d may be either loosely mounted on the pin e or se-

cured on the end thereof, and indeed many modifications might be made without departing from the spirit of my invention; but

What I claim, and desire to secure by Letters Patent of the United States, is—

1. In a device of the class described, the combination of a pail having imperforate sides, with a handle or bail therefor, and means for securing said handle to said pail without perforating the same comprising gripping-plates disposed adjacent to each other on the same side of each of the ends of said handle or bail, and means for moving said gripping-plates toward and away from each other, substantially as described.

2. In a device of the class described, the combination with the handle, of means, suspended thereby for detachably securing the handle to the wall of a bucket or similar vessel without perforating the same, comprising downwardly-extending gripping-plates disposed adjacent each other on the same side of each of said handle ends and operative transversely thereof, relatively to each other, for the purpose set forth, one of said gripping-plates being provided with a laterally-projecting indenting-flange at the lower end thereof adapt-

ed to engage the wall of the bucket or similar vessel on the opposite side from and immediately below said other gripping-plate when 30 clamped in position.

3. In a device of the class described, the combination with the handle having apertured ends, of a hollow bearing or sleeve adapted to loosely fit in each of the apertured ends of 35 said handle, said sleeve provided with a centrally-apertured annular flange or gripping-plate, a pin passing through said sleeve and gripping-plate, a second gripping-plate supported by said pin adjacent said first gripping-plate, and provided with an inwardly-projecting flange at the lower end thereof for indenting and securely fastening itself to the wall of a bucket or vessel when clamped thereto, and means for moving said pin transversely of said handle for clamping said gripping-plates.

In testimony whereof I affix my signature in presence of two witnesses.

ALEXANDER RATTRAY AYSON.
